UNITED STATES PATENT OFFICE.

CHARLES S. COLEMAN, OF LOS ANGELES, CALIFORNIA, ASSIGNOR OF ONE-FOURTH TO
R. S. BERRY, OF LOS ANGELES, CALIFORNIA.

BEADING TOOL.

Application filed April 17, 1922. Serial No. 553,309.

To all whom it may concern:

Be it known that I, CHARLES S. COLEMAN, a citizen of the United States, residing at Los Angeles, in the county of Los Angeles and State of California, have invented new and useful Improvements in Beading Tools, of which the following is a specification.

My invention relates to a device for forming beads or flanges on the ends of boiler flues the principal object of my invention being to provide a relatively simple, practical and efficient tool that may be readily manipulated and which will be effective in forming that portion of the flue that projects beyond the flue sheet into a bead or flange of uniform size and contour.

A further object of my invention is to provide a flue beading tool that will perform its intended functions without in any wise affecting or rupturing the joint that is formed between the flue and sheet by the expanding tool.

A further object of the invention is to provide simple and efficient means whereby the beading tool is firmly retained in the same relative position at all points throughout its circular path of travel, during the formation of a bead on the end of a flue.

With the foregoing and other objects in view, my invention consists in certain novel features of construction and arrangement of parts that will be hereinafter more fully described and claimed and illustrated in the accompanying drawings, in which:—

Figure 1 is a sectional view showing parts of a flue and flue sheet, my improved beading tool, and a portion of a pneumatic hammer that is utilized in operating the tool.

Fig. 2 is a cross section taken on the line 2—2 of Fig. 1.

Fig. 3 is a perspective view of the hammer or bead forming member of the device.

Fig. 4 is a perspective view of the guide block for the hammer or bead forming tool.

Fig. 5 is a perspective view of the flue expanding tool and its tapered pin or mandrel and which latter serves as a support or journal for the beading tool guide block.

Fig. 6 is an elevational view of a modified form of the beading tool guide block.

Referring by numerals to the accompanying drawings which illustrate a practical embodiment of my invention, 10 designates a flue sheet having an opening 11 in which is seated the end of a flue 12. A gasket 13

is seated in the opening 11 between the sheet 10 and flue 12 and the end portion of the latter is expanded in the opening in any suitable manner preferably by means of a sectional cylindrical expanding tool such as 14, the sections of which are forced radially outward by means of a tapered pin or mandrel 15.

Obviously, this pin or mandrel when seated in the tool 14 occupies a position coaxial with the flue 12 and the outer end portion 16 of said mandrel is cylindrical in form so as to serve as a journal for the beading tool guide block 17 which is formed with an opening 18 that receives portion 16 of mandrel 15. By virtue of this arrangement the guide block is supported so as to revolve about the axis of the mandrel and likewise the axis of the flue.

Formed through the upper portion of 75 guide block 17 is an aperture 19, the axis of which is disposed at a slight angle relative to the axis of opening 18.

Arranged for sliding movement through aperture 19 is the cylindrical body portion 80 20 of the beading tool, said body being provided on its forward end with a head 21 and the outer face of the latter being provided with a transversely disposed bead forming groove 22.

The rear end portion of the beading tool body is formed into a shank 23 that is adapted to be received by the tool engaging member of a pneumatic hammer 24.

Formed in the upper portion of block 17 90 is a longitudinally disposed slot 25 into which projects the outer portion of a pin 26 that is seated in the tool body 20. Thus the beading tool is mounted for reciprocatory movement within guide block 17 and 95 retained against rotary movement therein.

In the operation of my improved beading tool the parts are assembled as illustrated in Fig. 1, and as the pneumatic hammer is operated in the usual manner the blows of the 100 piston or plunger are received by the rear end of shank 23 and as a result the transverse recess 22 in the face of head 21 of the tool directly engages the end of the flue that projects beyond the sheet and beads the projecting end downwardly onto the face of the sheet immediately adjacent to the opening 11.

During this beading operation the hammer is manipulated so that guide block 17 110

that performs the functions of a carrier swings about the mandrel as an axis and during this movement the beading tool maintains the same relative position throughout the entire circular path of travel. As the expanding device or wedging member is tightly wedged in the tube by the operation of expanding the same the tube is firmly held at its junction with the walls of the bore in the flue sheet to resist the shocks occasioned by the beading operation.

Instead of providing a pin and slot connection between the beading tool and the guide block 17 as described, said guide block may be provided with a square or non-circular opening as illustrated in Fig. 6 and the body of the beading tool is made square or non-circular in cross section.

20 A flue beading tool of my improved construction is comparatively simple, may be easily and cheaply produced and may be advantageously employed in the rapid formation of beads on the ends of flues seated in 25 flue sheets, without the attendant danger or liability of breaking or rupturing the joints between the expanded ends of the flues and the sheets. Obviously, the construction of 30 the device may be modified in details without departing from the spirit of my invention, the scope of which is set forth in the appended claims.

I claim as my invention:—

- 35 1. A flue beading device comprising a member insertable in the end of a flue to be beaded adapted to be expanded into engagement with the flue, a pin embodied in said member projecting axially from the end of the flue, a guide block turnable on said pin, 40 a reciprocal tool shank slidably carried on said guide block and held against rotation thereon, and a head on said shank having a bead forming groove adapted to operate on the end of the flue.
- 45 2. A flue beading device comprising a member insertable in the end of a flue to be beaded, adapted to be expanded into engagement with the flue, a pin embodied in

said member projecting axially from the end of the flue, a guide block turnable on 50 said pin, a reciprocal tool shank slidably carried on said guide block and held against rotation thereon, and a head on said shank having a bead forming groove adapted to operate on the end of the flue, said guide 55 block being freely revolvable in either direction around said pin.

3. A flue beading device comprising an expansive member insertable in the end of a flue to be beaded, a pin projecting from said 60 member axially thereof, a guide block having a pair of openings therein one of which is adapted to slidably receive the outer end of said pin, a tool shank reciprocally mounted in the other opening and held against rotation therein, and a head on said shank having a bead forming groove adapted to engage the end of a flue in 65 which the expansive member is inserted.

4. In a flue beading tool, a guide block 70 having a pair of openings therein, a pin adapted to extend into one of said openings on which the guide block is freely turnable, means for supporting said pin coaxially with a flue to be beaded, a tool shank 75 slidable longitudinally in the other opening in said guide block and held against rotation, and a head on said shank having a bead forming groove on its outer face adapted to engage the end of a flue from which said 80 pin projects.

5. In a flue beading tool, a guide block having a pair of openings therein, a pin adapted to extend into one of said openings on which the guide block is freely turnable, 85 means for supporting said pin coaxially with a flue to be beaded, a tool shank slid- 90 able longitudinally in the other opening in said guide block and held against rotation, and a head on said shank having a bead forming groove on its outer face adapted to engage the end of a flue from which said pin projects, said tool shank extending at an angle to the axis of said pin.

CHARLES S. COLEMAN.
